US00D880594S

(12) **United States Design Patent** (10) Patent No.: **US D880,594 S**
(45) Date of Patent: ** Apr. 7, 2020

(54) **DIGITAL SIGNAGE**

(71) Applicant: **LG ELECTRONICS INC.**, Seoul (KR)

(72) Inventors: **Hongseok Kim**, Seoul (KR); **Areum Kwon**, Seoul (KR); **Hewon Kihl**, Seoul (KR); **Sechang Park**, Seoul (KR); **Sangwon Yoon**, Seoul (KR); **Yongho Lee**, Seoul (KR)

(73) Assignee: **LG ELECTRONICS INC.**, Seoul (KR)

(**) Term: **15 Years**

(21) Appl. No.: **35/505,957**

(22) Filed: **Apr. 27, 2018**

(80) **Hague Agreement Data**

Int. Filing Date: **Apr. 27, 2018**

Int. Reg. No.: **DM/101094**

Int. Reg. Date: **Apr. 27, 2018**

Int. Reg. Pub. Date: **Nov. 2, 2018**

(30) **Foreign Application Priority Data**

Oct. 27, 2017 (KR) 30-2017-0050050

(51) **LOC (12) Cl.** **20-02**
